US0D1103781S

(12) United States Design Patent (10) Patent No.: US D1,103,781 S
(45) Date of Patent: * Dec. 2, 2025

(54) BOTTLE

(71) Applicant: Homecourt Inc., Santa Monica, CA (US)

(72) Inventors: Courteneay Cox, Malibu, CA (US); Sarah Jahnke, Dallas, TX (US); Nick Axelrod-Welk, Los Angeles, CA (US)

(73) Assignee: Homecourt Inc., Santa Monica, CA (US)

() Term: 15 Years

(21) Appl. No.: 29/982,434

(22) Filed: Jan. 6, 2025

Related U.S. Application Data

(63) Continuation of application No. 29/952,947, filed on Jul. 18, 2024, now Pat. No. Des. 1,061,261, which is a continuation of application No. 29/883,223, filed on Jan. 25, 2023, now Pat. No. Des. 1,041,320.

(57) CLAIM

The ornamental design for a bottle, as shown and described.

DESCRIPTION

FIG. 1 is a front, upper, left perspective view of a bottle of our new design;

FIG. 2 is a rear, lower, right perspective view;

FIG. 3 is a left view thereof;

FIG. 4 is a right view thereof;

FIG. 5 is a front view thereof;

FIG. 6 is a rear view thereof;

FIG. 7 is a top view thereof; and,

FIG. 8 is a bottom view thereof.

Broken lines of equal length (e.g., dash-dash) represent unclaimed subject matter and form no part of the claimed design. Broken lines of unequal length (e.g., dash-dot) define bounds of the claimed subject matter and form no part of the claimed design.

1 Claim, 8 Drawing Sheets
